UNITED STATES PATENT OFFICE.

SAMUEL CLELAND DAVIDSON, OF BELFAST, IRELAND.

FLARE-LIGHT SHELL.

1,306,407.

Specification of Letters Patent. Patented June 10, 1919.

Application filed June 27, 1917. Serial No. 177,205.

To all whom it may concern:

Be it known that I, SAMUEL CLELAND DAVIDSON, a subject of the King of Great Britain and Ireland, and resident of Belfast,

5 Ireland, merchant, have invented certain new and useful Improvements Relating to Flare-Light Shells, of which the following is a specification.

This invention relates to the construction 10 and adaptation of what may be defined as "flare-light shells" for brilliantly lighting up at night, for say a minute or more, a considerable area around where the shell lands on the ground, at the end of its flight.

15 The present invention consists in a modified construction of the explosive shell described and shown in my pending specification of Letters Patent Serial No. 126,434 filed Oct. 16, 1916, (hereinafter referred to 20 as my previous specification).

In my said previous specification, the explosive shell therein described is fitted with a time fuse projecting through a fuse plug, which is firmly attached to the base of the 25 shell, and forms a constituent part thereof, but which is detachably connected to the cartridge case containing the powder for propelling the shell from the weapon which is therein referred to as the gun or pistol.

30 The time fuse itself so communicates at its rear end with the explosion chamber in the cartridge case that the explosion therein of the propellant charge ignites it, and subsequently the other end of the fuse ignites the 35 bursting charge within the shell.

In the present invention, my hereinafter described improvements pertain to the constructive details of the body of the shell, which is loaded with a compound of mag-

40 nesium, or other suitable flare-light powder (hereinafter called "flare powder") and to the attachment of the fuse plug to the base of the shell, also to the ignition of the flare powder by the fuse, and the wad for closing

45 the top end of the shell, but the propellant cartridge case for the shell, and method of firing its contained charge, and the ignition of the time fuse leading therefrom, by means of the explosion of the propellant charge,

50 remain practically as described in my said previous specification.

The object of my present improvements is to provide a flare-light shell, which can be effectively ignited at its top end by means 55 of a time fuse, and which can be thrown at night to the end of its flight without burst-

ing forth into its brilliant flare-light until the termination of the period for which the time fuse is adjusted, and at or near to where it lands on the ground. 60

According to this invention, and instead of using as described in my previous specification, an iron shell body with a bursting charge of powder rigidly inclosed therein, so that on explosion it bursts the body of 65 the shell into shrapnel-like pieces, I now employ a cylindrical shell body made of suitable light material, such as cardboard, and firmly mount the base end of it on a metal (preferably iron or steel) fuse plug, 70 which is detachably connected to the metal cartridge case containing the propellant charge, said fuse plug having a time fuse contained within a fuse tube which projects through it to the top end of the flare powder 75 charge, and in order to enhance the igniting charge, and in order to enhance the igniting flame of the fuse a small space is left between its end and that of the fuse tube into which a priming of slow burning powder (such as mealed powder) is inserted, and 80 held therein with a small wad of flannel or other suitable material, so that on the fuse igniting this priming it gives off a rich flame which insures a full ignition of the top surface of the flare powder. 85

The ignition, however, of flare powder by means of a time fuse, when said powder is within a completely inclosed chamber to which there is practically no access of atmospheric air, is difficult and unreliable, as 90 it is not a self-oxidizing powder, and requires atmospheric aid for its combustion, consequently in order to effect its ignition within the shell it is necessary to provide a sufficient body of air close to where the time fuse emits its fire into the top end of the shell, to enable the flare powder to ignite over the whole surface of the charge, and at the same time develop enough pressure from the resulting gaseous products of combustion to eject the wad closing the end of the shell, and thereby give free access of 95 the atmosphere to the whole end surface of the flare powder charge within the body of the shell. 100

To accomplish this method of igniting flare powder while it is completely inclosed inside the shell, and by means of a time fuse, I provide the necessary supply of air within the top end of the shell, and in front 110 of where the time fuse emits its fire, by the employment of a wad which constitutes a

tight fitting closure of the top end of the shell (hereinafter referred to as the "air inclosing wad") and between which and the surface of the flare powder charge there is 5 a distance piece, preferably annular (hereinafter called the "annulet") whereby a sufficient amount of air space is provided to enable the flare powder to properly ignite, and develop sufficient pressure of gaseous 10 products of combustion to eject the air inclosing wad. A disk of fine mesh wire web, or woven textile fabric, or other suitable foraminous material, or thin paper, (hereinafter called the "retaining disk") is placed 15 on the surface of the flare powder charge to retain it in position, and prevent any loose particles of its top layer being shaken up into the air space between the air inclosing wad and said retaining disk when the 20 shell is in transport, or being handled.

When charging the shell, the flare powder is packed firmly around the fuse tube from the base of the shell up to the level of the firing end of the fuse tube, so that when 25 the priming of slow burning powder in top end of the fuse tube ignites, the flash passes through and spreads over the retaining disk, developing a back pressure in the air space whereby the flash is driven down again 30 through the retaining disk into and ignites the whole surface of the flare powder, and simultaneously ejects the air inclosing wad from the top end of the casing, giving free access of the atmosphere over the whole 35 surface of the flare powder, which thereafter continues to burn with its full brilliancy of combustion until the whole charge is consumed, which, according to the quantity and depth of the charge contained in the shell, 40 will be for one or more minutes as may be provided for when the shell is being loaded.

A further part of my invention is to so devise the construction of the shell as a whole that when discharged at a suitable angle of elevation, it will always at the termination of its flight land on the ground upon 45 its base end, so that its top end, from which the flare bursts forth, should be pointing approximately upward, because if it were to so land that its top end got buried in the ground, no atmospheric air could then reach the flare powder which, not being self-oxidizing, cannot burn without atmospheric aid, and even if already burning before it 50 reaches the ground, its further combustion would at once cease.

Accordingly to insure that the shell will land on its base end, with its top end more or less pointing upward, the shell is so constructed as a whole that relatively to its 55 length its center of gravity is so much farther from the top than from the base end, that although said top end is of course leading when the shell leaves the propelling 60 weapon, it soon turns end for end and comes

down at the termination of its flight with the base end leading, and lands thereon.

In so locating this center of gravity, the shell body, which is of very light construction, (usually of cardboard or cartridge 70 paper) and preferably of parallel diameter from end to end, is mounted upon a metal fuse plug of sufficient weight to render the length from the base end to said center of gravity so much less than that from the top 75 end, that the resistance due to air friction on the top end is relatively so much greater than on the shorter length at the fuse plug end, that (like the effect of feathers on an arrow) the top end quickly becomes, and thereafter steadily remains, the trailing or tail end of the shell, with the heavier fuse plug end leading, so that the shell consequently lands upon the ground on its base 80 end, and (provided the whole shell does not 85 get completely buried, as may happen in very soft ground) its flare when ignited will continue to burn with full brilliancy until the whole charge of the flare powder is exhausted.

The type of weapon which I preferably use for projecting the herein described shell is that shown and described in my British patent specification No. 13511 of 1915, and in a pending application for U. S. A. patent 90 filed June 26, 1917, Serial No. 177,013, because with this weapon, when firing at a constant angle of elevation, different ranges can be obtained with fairly close accuracy, while still using a constant charge of propellant, but it can also be fired from other forms of breech-loading smooth bore weapons, provided the barrel is of suitable length and bore, and that the detachable cartridge case is retained in, and after firing can be 95 ejected from the breech.

Reference to the accompanying drawings will more fully explain the nature of my invention, and how it is carried into effect.

Figure 1 is a longitudinal section of the 110 flare light shell showing the propellant cartridge case with fuse plug attached thereto, and the hereinbefore described air inclosing air wad at top end of the shell. The lower part of the metal fuse tube projecting 115 through the fuse plug into the flare powder, and containing the time fuse, is shown in elevation, but its upper end is shown in vertical section so as to indicate the position of the priming charge on top end of fuse, which 120 is held within the end of the fuse tube by a small wad.

Fig. 2 is a part longitudinal section of the upper end of the flare light shell, showing an alternative type of the air inclosing wad at 125 the top end of the shell.

Fig. 3 is a part longitudinal section of the upper end of the flare-light shell, showing a further alternative type of the air inclosing wad at the top end of the shell.

Fig. 4 is a part longitudinal section of the upper end of the flare-light shell, showing a modification of the air inclosing wad, wherein the annulet is formed as a part of the wad itself.

The letters indicating the various component parts are the same in each figure, and are as follows:—

- a* is the cardboard or cartridge paper body 10 of the flare-light shell (hereinafter called "casing") which is of such diameter as to constitute a free sliding fit within the barrel of the propelling weapon, and which is firmly attached by a tight sliding fit on to 15 the recessed part of the fuse plug *b*. The extreme end of the base of the body *a* abuts against a collar-like flange *b'* on the fuse plug *b*, the diameter of which is a sliding fit to the bore of the propelling weapon, 20 and prevents the cardboard casing from being blown off the fuse plug by the explosion of the propellant charge. The fuse plug *b* is formed with an annular flange *b*² extending toward the cartridge case *c*, fitting out- 25 side of and forming a close detachable joint with the terminal end of said cartridge case. *d* is a time fuse inclosed in a metal tube *d'* crimped in upon the fuse from immediately above the fuse plug for a portion of its 30 length, as shown at *d*², in order to prevent the fuse being displaced within the tube by the explosion of the propellant charge, the end of the fuse tube toward the cartridge case being expanded or otherwise secured 35 so as to make a flash-tight joint with the fuse plug *b*. The firing end of the fuse tube *d*², is shown in section to indicate the position of the priming of slow burning powder on end of fuse, and the retain- 40 ing wad *d*⁴, on top of the priming, *e* is the flare powder which is tightly packed inside the body *a* and around the fuse tube *d'*, and up to the top end of the fuse tube at about the level of the retaining wad *d*⁴. The re- 45 taining disk *f* is placed over the surface of the flare powder charge to prevent any loose particles therefrom being displaced into the air space between it and the air inclosing wad in top end of casing. *g* is the 50 air inclosing wad which is preferably made with a convex central projection on its interior, and an inverse cup-like concavity on its exterior surface with a rim flange *g'* on its outward and upward continuation. *h* 55 is annulet distance piece between the air inclosing wad *g* and the retaining disk *f*. This air inclosing wad is inserted as a tight fitting closure of the extreme terminal end of the casing.
- 60 It is to be understood that I do not limit myself to the exact dimensions or configuration hereinbefore described and illustrated in the accompanying drawings, which are to be considered as indicative only of the general operative and constructive principle on

which my invention can be applied in a practical form, and having now described the nature of my invention and how same is to be carried into effect, what I claim and desire to secure by Letters Patent is:—

1. In flare-light projectiles a casing adapted to hold flare-light powder, a fuse plug attached to the base of the casing, a fuse tube disposed in a hole in the fuse plug and extending some way into the casing, a fuse in said fuse tube adapted to be ignited at its lower end by the explosion of the propellant charge, and to contain at its upper end a priming of slow burning powder for igniting the charge of flare powder, a retaining disk of foraminous material, or paper over the surface of the flare powder, between which disk and an air inclosing wad in the top end of the casing, an air space is provided for the supply of air to assist the initial ignition of the top surface of the flare powder charge.

2. A flare-light projectile, as claimed in claim 1, characterized in that the marginal edge of the inner face of the air inclosing wad, when pushed into the open top end of the casing, has between it and the rim of the retaining disk an annular or other suitable form of distance piece, whereby said retaining disk is held firmly down upon the flare powder at or near to the inner circumference of the casing, and a definite area of air space thus provided between the surface of the flare powder and the inner face of the air inclosing wad.

3. A flare-light projectile comprising a casing, a charge of flare-light powder therein, and a fuse for lighting the top of such powder, having its center of gravity in relation to the length of the projectile substantially nearer the base or fuse plug end than the top end, whereby it tends to reverse its position during flight and to fall with its base on the ground, so that it may stand upright while burning.

4. A flare-light projectile comprising a projectile casing, a charge of flare-light powder therein, a base fuse plug, a time fuse leading upward therefrom and adapted to ignite the top portion of the flare powder, and a closure at the top end of the casing removed from the charge of flare powder to form an air chamber inclosing a supply of air to assist the initial combustion of the flare powder.

5. A projectile according to claim 4, having between the fuse and top closure a charge of powder to burn within the air chamber to ignite the top of the flare powder.

6. A projectile according to claim 4, having its top closure inclosing only a portion of the air required for the combustion of the flare powder, and adapted to be blown off as such combustion proceeds.

7. A projectile according to claim 4, hav-

ing on top of the charge of flare powder a retaining disk, and an annular distance piece introduced between such disk and the top closure to form the air chamber.

5 8. A projectile according to claim 7, with the annular distance piece separated from the side walls of the projectile casing.

In witness whereof, I have hereunto signed my name in the presence of two subscribing witnesses.

SAMUEL CLELAND DAVIDSON.
